RECEIVING DEVICE

Frank Blythen, Hayes, and John Hardwick, West Drayton, England, assignors to Electric and Musical Industries Limited, Hayes, England, a company of Great Britain

Application February 12, 1934, Serial No. 710,802
In Great Britain February 13, 1933

3 Claims. (Cl. 178—7.5)

The present invention relates to cathode ray tubes such for example as are used in television receivers.

Such a tube may comprise a heated cathode, a control electrode, means for accelerating the electron ray and bringing the electrons to a focus on a fluorescent screen and means for deflecting the ray over the screen.

The received picture signals are applied between the control electrode and cathode, to vary the negative potential of the grid in relation to the cathode, and serve to increase and decrease the intensity thereof whilst the ray is swept, by the deflecting means, over the screen in harmony with the scanning device at the transmitter.

In such tubes it is found that the light intensity-grid voltage characteristic is very curved, the rate of change of light intensity being considerably greater for less negative grid potentials, 20 that is higher light intensities, than for more negative grid potentials, that is lower light intensities. It is usually necessary to bias the control grid relatively to the cathode in such a way that a picture signal of maximum amplitude in the 25 "black" direction reduces the intensity of the ray substantially to zero and when this is done it is found that, owing to the curvature of the characteristic, gradations of intensity in the darker parts of the reproduced picture are masked 30 whilst, in the lighter parts, they are unduly accentuated.

It is an object of the present invention to remove or reduce the errors introduced by a non-linear characteristic in a cathode ray tube.

It is a further object to provide a method of transmitting and receiving images of objects wherein picture signals are distorted, either at the transmitter or at the receiver, before being applied to a non-linear reproducing device such as 40 a cathode ray tube, in such manner as to compensate, at least partially, for the non-linear light intensity-modulating voltage characteristic of said reproducing device.

Yet another object of the present invention is 45 to provide television receiving apparatus comprising a cathode ray tube or a like reproducing device having a non-linear light intensity-modulating voltage characteristic and means for distorting picture signals, before application to said device, in such manner as to compensate, at least partially, for the non-linearity of said device.

Yet another object of the present invention is 50 to provide television transmitting apparatus comprising means for generating picture signals corresponding to the light and shade of the object

and means for increasing the amplitude of signals representative of the darker portions of the object as compared with signals representative of the lighter portions of the object.

An embodiment of the invention will now be described with reference to the accompanying drawing in which

Fig. 1 is a circuit diagram of television receiving apparatus arranged in accordance with the present invention,

Fig. 2 is a graph of the light intensity-grid voltage characteristic of a known form of cathode ray tube, light intensity being plotted as ordinates and grid voltage as abscissae, and

Fig. 3 is a graph of the anode current-grid voltage characteristic of a thermionic valve, anode voltage being plotted as ordinates and grid voltage as abscissae.

Referring now to Fig. 1, the received picture signals are applied to the grid circuit of a screen-grid valve 1, the anode circuit of this valve being coupled to the control grid circuit of a cathode ray tube 2. The positive potential applied to the screening grid 3 relative to the cathode 4 of the valve 1 and the value of the anode resistance 5 are both lower than usual. By suitably biasing the control grid 6 of the valve 1 relative to the cathode 4, the shape of the anode current-grid voltage characteristic of this valve, shown in Fig. 1, can be made complementary to the shape of the light intensity-grid voltage characteristic of the cathode ray tube 2, shown in Fig. 3, so that the signals applied to the grid 7 of the cathode ray tube 2 are distorted, signals in the "black" direction appearing in the anode circuit of the tube 2 at greater intensity than signals in the "light" direction.

The valve 1 is used also to rectify an incoming carrier modulated with picture signals. This is done by arranging the valve, in the manner illustrated, as a grid-leak rectifier.

When the distortion introduced by the cathode ray tube 2 is compensated for in the manner described, the negative bias upon the control grid 7 of the cathode ray tube 2 may be made less than is usually necessary whilst still obtaining good reproduction of black portions of a picture. As a consequence of this, an increase in modulation does not produce such an increase of background brightness as results from working with higher values of bias. Any change that remains may, however, be compensated for by biasing the grid 7 of the cathode ray tube 2, as shown, from the D. C. potential drop along the anode resistance of the distorting valve.

For the reception of a carrier frequency of about 40 megacycles the following arrangement is satisfactory:

A selector circuit 8 tuned to the carrier frequency to be received has one terminal connected to the cathode 4 of the screen-grid valve 1 and the other terminal connected through a condenser 9 of 25 micromicrofarads shunted by a resistance 10 of 10,000 ohms. The screening grid 3 is maintained at a potential of 40 volts relative to the cathode 4 and the anode 11 is connected through a resistance 5 of 10,000 ohms to a point at 200 volts relative to the cathode 4. The end of the resistance 5 remote from the anode 11 is connected to the cathode 12 of the cathode ray tube 2 and the other terminal of the resistance 5 is connected through a high frequency choke coil 14 to the control grid 7 of the cathode ray tube 2.

20 A receiver of this kind is of particular advantage for the reception of motion picture films because it is common practice in the film industry to develop films in such manner that detail in bright portions of the picture is brought out, 25 or amplified, as it were, relatively to the detail in the darker or more opaque portions of the pictures. This is done because pictures projected upon a screen from films developed in this way appear more natural to the eye. Therefore it is 30 essential that, when films of this kind are transmitted, the receiver should not still further emphasize detail in bright portions of the picture, as would be the case if distortion of the received signals is not effected as is described herein.

35 Although it is preferred to carry out the correction of the picture signals according to the present invention at the receiver, in some cases the correction may be effected before transmission.

40 We claim:

1. The method of compensating for distortion in reproducing electro-optical images upon the viewing screen of a cathode ray tube having

normally non-linear light intensity modulating voltage characteristics which comprises the steps of applying from an amplifying system to the control circuit of the electro-optical reproducing device controlling signals and modifying the signals prior to applying the same for control purposes by operating the amplifying system upon that portion of its anode current-grid voltage characteristic which has a curvature substantially complementary to the curvature of the 10 light intensity modulating voltage characteristic of the electro-optical reproducing device. 5

2. The method of compensating for distortion in reproducing electro-optical images upon the viewing target of a cathode ray tube having normally non-linear light intensity modulating voltage characteristics which comprises the steps of 15 amplifying and non-linearly detecting controlling signals to provide an output characteristic complementary to the non-linearity of the cathode ray tube and applying the amplified detector signals to the control circuit of the cathode ray tube to modulate the electron beam developed in the tube whereby a substantially linear response is obtained. 20

3. In a television system wherein a non-linearly responsive cathode ray tube having a control circuit is used to produce electro-optical image representations and wherein a grid leak multi-grid thermionic tube having input and output circuits is arranged to receive upon the input circuit signals representative of the electro-optical effects, the method steps of operation which comprise non-linearly detecting the received signals in a manner complementary to the non-linearity of the cathode ray tube and feeding the detected signals from the output circuit of the thermionic tube through a frequency discriminating path to the control circuit of the cathode ray tube so that electro-optical image representations are substantially linearly reproduced. 30 35 40
